MANIFOLDING BOOK

Arthur E. Benson, Manville, R. I., assignor to
 McKenzie Engraving Company, Boston, Mass.,
 a corporation of Massachusetts

Application March 5, 1936, Serial No. 67,208

7 Claims. (Cl. 282—23)

The present invention relates to manifolding books and has for its object the production of a book of this character which may be used for several purposes where triplicate copies of any particular data are required, as for instance, the recording of a plurality of orders for articles which must be subsequently made or partly made before shipment.

This object is attained by constructing a book in the manner illustrated in the accompanying drawing.

For the purpose of illustrating the invention, one preferred form thereof is illustrated in the drawing, this form having been found to give satisfactory and reliable results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawing—

Figure 1 represents a manifolding book embodying the principles of the present invention, one sheet of which is shown unfolded and spread out.

Figure 2 represents an elevation of a portion of said book with the sheets thereof folded as the book would be when not in use.

Figure 3 represents an elevation of a portion of one of the sheets showing the rear face thereof.

Figure 4 represents in diagram one of the sections of the book with carbon sheets interposed between the folds of the sheets, and

Figure 5 represents in diagram an end view of the book.

Similar characters indicate like parts throughout the several figures of the drawing.

In the drawing, 10 is a paper sheet having a plurality of lines of perforations 11, 12, 13 and 14, extending from top to bottom thereof, thereby dividing said sheet into an inner section 15, an intermediate section 16, an outer section 17, and an extension 18 projecting from the outer edge of the outer section 17.

A plurality of these sheets 10 are bound together between strips 19 with staples 20 extending through the various sheets 10 and said strips 19.

Bound into the book and extending over the section 15 of each sheet is a carbon paper 21 and over this carbon paper 21 and the upper sheet 10 is the cover 22 which has a width suffi-

cient to cover the sheets 10 when folded in the manner to be hereinafter described.

The various sheets 10 composing the book bound together as above stated are numbered consecutively as indicated at 23, and any informative characters may be printed or written upon the sections 15, 16 and 17, and the extension 18.

The characters on the intermediate section 16 are printed on the reverse face of the same, as indicated in Fig. 3 of the drawing, so that when said intermediate section 16 is folded over onto the section 15 along the line of perforations 12 and the section 17 is folded over upon the intermediate section 16 along the line of perforations 13, as shown in Figs. 2 and 4 of the drawing, the printed characters on the various sections and the extension 18 are all facing in the same direction.

When in this position the carbon paper 21 will be superimposed upon the section 15 with the extension 18 beyond the outer edge of said carbon paper 21.

At the rear of the book are bound several other carbon sheets 24 perforated from top to bottom so that a portion of the same equal to the width of one of the sections 15, 16 and 17 may be detached from the part bound into the book and this detached portion may then be interposed between the intermediate section 16 and the outer section 17 with its outer edge registering with the outer edge of the section 15.

Each of the sections 15, 16 and 17 are divided by lines 25 into ten panels 26 in longitudinal alignment and numbered from top to bottom of each section by the designating numerals 27.

Opposite the lines 25 and in alignment therewith is a plurality of perforations 28 extending across the extension 18.

By means of the line of perforations 14 and 28 a plurality of slips 29 are formed which may be detached from the section 17 and also from each other.

These slips 29 have designating numerals 27, one to ten, corresponding to the numerals on the panels 26 which said slips are opposite.

When the sheets 10 are folded into the position shown in Figs. 2 and 4 any information desired may be written on one of the slips 29 and the same and other information may be written on the panel of the same number of the outer section 17.

When this information is written on either panel 26 of the outer section 17, the same information will be simultaneously transferred to

the sections 16 and 15 owing to the carbon sheets 21 and 24 disposed beneath the sections 17 and 16.

When the book is not in use the sheets are all 5 in folded position as indicated in Fig. 5 of the drawing and the cover 22 extends to the right hand edge 30 of the extension 18.

A book thus constructed may be utilized for many different purposes, as for instance, it might 10 be used as an order book where small numbers of inexpensive articles are to be made or partly made in accordance with an order received from a customer and the amount of the order would not warrant expensive bookkeeping.

15 An order received from a customer would be inserted on slip 1 for instance of the extension 18 and the same and other data written on the panel 1 of section 17.

All the data which are printed on the panel 20 1 of section 17 would be transferred to panels 1 of the sections 15 and 16.

The next order received would be placed on slip 2 of extension 18 and panel 2 of section 17, and so on until all of the slips 1 to 10 have 25 been filled out, the customer in each case taking the slip to show when he comes to the store to claim the finished articles.

When all of the slips 1 to 10 of one sheet have been filled out, sections 16 and 17 of the sheet 30 are then detached from section 15 which may be retained in the book if desired as a matter of record at the place of business where the order is given, and these sections 16 and 17 are sent to the office of the firm where the work is to be done.

35 If desired one carbon paper 21 may be used for several of the sheets 10 and the upper sheet in this case is removed from the book in its entirety when once filled out with the desired information. When the upper sheet 10 is filled in 40 and it is detached from the book the carbon paper 21 will rest on section 15 of the inner sheet 10.

Section 16 is detached at the factory from section 45 17 and sent to the workshop to have the order filled, and when the order has been filled and ready to be sent to the retailer, the articles are forwarded to the retailer with the section 17 which acts as an invoice in lieu of a bill.

Consequently, in the bookkeeping divisions of 50 both the retailer and manufacturer, there is no necessity for entering each individual item on the ten panels but on the contrary it is only necessary to enter a single item and that is "No. 11" which 55 includes all of the articles included on the entire section 17.

While the original section 17 is sent to the retailer as an invoice, the intermediate section 16 is kept by the firm doing the work, and the inner section 15 is always kept by the retailer as 60 a part of his records.

By the use of a book thus constructed, the bookkeeping of both the retailer and the firm doing the work is greatly simplified.

65 In Fig. 1 of the drawing, panel 5 has indicated thereon certain designating characters used for one particular purpose.

In each book all of the various slips in section 18 have the same designating characters there- 70 on.

It is believed, however, unnecessary to repeat these data on all of the slips.

Likewise, in Fig. 1 on the panels 5 of sections 75 15 and 17 are shown other designating characters used for a particular purpose, and when

properly filled out on the dotted lines give desired information.

It will be understood that all of the panels on sections 15, 16 and 17 in each book have exactly the same characters as shown in panels 5 of Fig. 1 of the drawing. 5

Any other data may be applied to the various panels and slips to be used for an entirely different purpose without changing the scope of the invention. 10

Having thus described my invention, I claim—

1. A manifolding book comprising a plurality of bound-in sheets divided into three detachable sections with similar printed characters similarly located on each section and normally folded to cause said characters on the three sections to face in the same direction and in register, a bound-in carbon paper between the inner and intermediate sections, and another perforated bound-in carbon paper at the back of the book having a detachable portion adapted to be interposed between said intermediate and outer sections. 15

2. A manifolding book comprising a plurality of bound-in sheets divided into three detachable sections with similar printed characters similarly located on each section and normally folded to cause said characters on the three sections to face in the same direction and in register and the inner section being detachable from the bound-in portion of each sheet, a bound-in carbon paper between the inner and intermediate sections and a loose carbon paper interposed between said intermediate and outer sections. 20

3. A manifolding book comprising a plurality of bound-in sheets divided into three detachable sections with similar printed characters similarly located on each section and normally folded to cause said characters on the three sections to face in the same direction and in register, a bound-in carbon paper between the inner and intermediate sections and another carbon paper bound into the book and adapted to be detached and interposed between said intermediate and outer sections, all of said sections being divided into ten panels in longitudinal alinement and numbered consecutively from top to bottom and all of said panels in alinement on all of said sections having a like number. 35

4. A manifolding book comprising a plurality of bound-in sheets divided into three detachable sections with similar printed characters similarly located on each section and normally folded to cause said characters on the three sections to face in the same direction and in register, a bound-in carbon paper between the inner and intermediate sections, and another carbon paper interposed between said intermediate and outer sections, all of said sections being divided into ten panels in longitudinal alinement and numbered consecutively from top to bottom, said panels in alinement on all of said sections having a like number, the outer section of each sheet having extending from its outer edge and beyond said carbon paper ten slips opposite said panels and similarly numbered. 45

5. A manifolding book comprising a plurality of bound-in sheets divided into three detachable sections with similar printed characters similarly located on each section and normally folded to cause said characters on the three sections to face in the same direction and in register, said sections being detachable from each other and the inner section being detachable from a portion of the sheet bound into the book, a bound-in carbon paper between the inner and intermediate 55

sections and a loose carbon paper interposed between said intermediate and outer sections, all of said sections being divided into ten panels in longitudinal alinement and numbered consecutively from top to bottom, said panels in alinement on all of said sections having a like number, the outer section of each sheet having at its outer edge beyond said carbon paper an extension provided with ten slips opposite said panels and 10 similarly numbered, said slips being detachable from said outer section and from each other.

6. A manifolding book comprising a plurality of bound-in sheets divided into three detachable sections with similar printed characters similarly 15 located on each section and normally folded to cause said characters on the three sections to face in the same direction and in register, a bound-in carbon paper between the inner and

intermediate sections and another bound-in carbon paper adapted to be interposed between said intermediate and outer sections after detachment from said book.

7. A manifolding book comprising a plurality of bound-in sheets divided into three detachable sections with similar printed characters similarly located on each section and normally folded to cause said characters on the three sections to face in the same direction and in register, a bound-in carbon paper between the inner and intermediate sections, a loose carbon paper interposed between said intermediate and outer sections, and a plurality of slips extending from the outer edge of the outer section and beyond said 15 carbon sheets, said slips being detachable from said outer section and from each other.

ARTHUR E. BENSON.
